UNITED STATES PATENT OFFICE.

ORVILLE M. MORSE, OF JACKSON, MICHIGAN; SARAH G. MORSE SPECIAL ADMINISTRATRIX OF SAID ORVILLE M. MORSE, DECEASED.

DUST-COLLECTOR.

979,987.

Specification of Letters Patent. Patented Dec. 27, 1910.

Application filed October 9, 1905. Serial No. 281,928.

To all whom it may concern:

Be it known that I, ORVILLE M. MORSE, a citizen of the United States, residing at Jackson, in the county of Jackson and State 5 of Michigan, have invented certain new and useful Improvements in Dust-Collectors, of which the following is a specification.

My invention relates to centrifugal dust collectors, and has for its general object to 10 provide a machine of large capacity in relation to its internal area, wherein the loss of power due to "back pressure" may be slight, and the separating action effective.

To these and other ends which will be 15 come apparent to those skilled in the art, I provide in my machine an area in which the dust-laden air, when tangentially introduced, tends to set up a normal or concentric vertical whirl, and I arrange at different 20 radial distances from the center of such area, in the upper plane thereof, a plurality of deflectors, one overlying the other, and disposed to prevent the establishment in said plane of the normal whirl and to cause to be 25 established in said area an eccentric vertical whirl, said deflectors serving to deflect practically dustless air into operative proximity to an air outlet, opening into the eccentric whirl, and to deliver the deflected dust- 30 laden air with reduced force into the path of the incoming air before it passes under the influence of the aforesaid vertical whirl.

For the most effective operation and simple construction, I prefer that one deflector 35 be disposed to deflect a dust-laden portion of air from its normal course within the containing structure, to a point in advance of the inlet, and that the other, inner deflector be disposed in overlying relation to 40 the first, to deflect a relatively dustless portion of air from radially within the first said deflected portion to a point farther in advance of the inlet to establish an eccentric vertical whirl excluding the first said 45 deflected air portion.

In the drawings I have accordingly shown such an embodiment of my invention, though it will be understood that the illustration is simply for purposes of full dis- 50 closure and without intent to limit my invention to the specific construction shown.

It will become obvious that numerous

changes might be made in the construction without departure from the spirit and scope of my invention.

Referring now to the drawings: Figure 1 is a central vertical section of a machine embodying my invention, taken on line 1-1 of Fig. 2 and showing the deflector-structure in elevation with parts broken away. Fig. 60 2 is a section on line 2-2 of Fig. 1 looking in the direction of the arrows.

Throughout the figures like numerals of reference refer to like parts.

To describe now the specific construction 65 shown, 5 indicates in general a confining structure or casing of suitable shape, wherein dust-laden air may rotate, comprising preferably a conical base 5^a, a head 5^b which may be cylindrical, or as shown, slightly 70 conical, and a deck 5^c, the whole including an area vertically communicating throughout. 6 indicates a tangential inlet to the structure, located contiguous to the deck thereof. 7 is a dust-outlet at the bottom or 75 apex of the base, 5^a, and 8 a purified air outlet in the deck 5^c. These parts are, in general, well known as a form of casing structure, and other forms of casing wherein moving dust-laden air may centrifugally 80 mass its dust might be employed in lieu thereof.

Within the area inclosed by the confining structure, in an upper level or plane thereof, I provide a plurality of deflectors two 85 such deflectors, indicated as 9 and 10, being provided in the specific embodiment shown. Said deflectors extend with reference to elevation from a plane contiguous to the deck to or below the plane of the bottom of the 90 inlet, and may be of substantially equal height, though as shown, I prefer that deflector 10 extend slightly below deflector 9. The deflector 9 is arranged to deflect a peripheral portion of the air, laden with dust, 95 inward in the machine and deliver it to the incoming air in advance of the inlet, and to this end extends, in plan, from a point contiguous to and preferably in contact with the wall 5^b of the casing, in a curved eccentric to the casing axis to some suitable point, preferably about half way around the casing from its starting point. The deflector 10, generally overlying the deflector 9, is 100

arranged at a less radial distance from the casing axis to deflect an inner, practically dustless portion of air into an eccentric path to cause to be formed at the top of the casing an eccentric vortical whirl, and to this end extends from a point out of contact with the deflector 9 and the casing wall in a curve eccentric to the casing axis and preferably eccentric also with respect to deflector 9, to some suitable point, preferably in advance of the end of deflector 9, (with respect to the direction of air movement). Thus there is left between deflectors 9 and 10 a space 11, preferably an "expansion" space gradually increasing in width in the direction of air movement, and in said expansion space I preferably provide means for positively causing the material in movement therein to take a downward course, such means being herein shown as an inclined top-plate 12, extending gradually downward from the deck of the casing. The deflectors 9 and 10 may, to good effect, be provided at their ends with out-turned lips 9' and 10' respectively, to stiffen the deflectors, and deflector 10 may be cut away at the top adjacent its end, as at 10°.

The outlet 8, opening into the eccentric whirl area within deflector 10, I prefer should be adjustable in position, although obviously it might be permanently located. For adjustability, therefore, I provide as part of the deck structure two rotatable plates 13 and 14, the former having therein an eccentric aperture wherein is nested the plate 14 and the latter having eccentrically located therein the outlet opening 8.

The deflector 10, may, if desired, be adjustable to vary the distance of its inner end from the casing axis, and to this end is pivoted as at 10°, at its radially outer extremity, its inner end having secured thereto a bolt 15, the head whereof overlies a slot 16 in a plate 16, partly covering the opening for ring 13, and affording a convenient support for the inner ends of deflectors 9 and 10.

17 indicates a clamping nut on the bolt 15 for securing the deflector in adjusted position.

In operation, dust laden air, blown tangentially into the area included within the confining walls of the casing tends to set up a vortical whirl therein concentric with the casing, but by the deflectors 9 and 10 the moving air body is diverted from its normal course and caused to set up in the top of the casing an eccentric vortical whirl, partly bounded by the deflector 10. It will be apparent that deflectors 9 and 10 jointly deflect substantially the whole air-body, the deflector 10 skimming away the practically dustless air and turning it into the eccentric vortical whirl into which the outlet 8 opens, and the deflector 9 keeping the pe-

ripheral dust-laden air-belt out of the incoming air adjacent the outlet and out of the vortical whirl. Thus the dust-laden air introduced into the casing is substantially entirely deflected, and is separated from the multiple deflectors, the dust laden part being maintained for a suitable distance out of the incoming current and then delivered to the incoming current or downward below it, while the practically dustless air is deflected into an eccentric vortical whirl from which it escapes practically unimpeded through the air outlet.

While I believe the broad conception of a machine operating as above described to be new and will broadly claim the same, some of the minor features of my machine shown are quite important from a practical standpoint.

The relative arrangement of the deflectors whereby the space 11 is made of increasing width I believe to be notable, as the expansion of the air therein slackened its speed and causes said dust-laden air to be delivered with reduced force to the incoming air current, at the end of the deflector 9, so that it does not seriously impede the entrance of incoming air. Furthermore, the expanding shape, in plan, of the area radially without the deflector 9, into which the dust laden air is blown, permits an expansion of the incoming air which decreases its density and enables the lighter dust particles to reach the casing wall with greater facility.

The dust carried into the machine with the air largely masses and drops below the plane of the deflectors in its initial partial circuit of the casing before reaching the deflectors, but such dust as is carried to the deflectors, massed by virtue of centrifugal action, is deflected by deflector 9 and thereby additionally massed, so that it passes close to deflector 9 into the space 11, the relatively-dustless inner air portion being deflected by deflector 10 to establish an eccentric vortical whirl as above described. The dust entering the space 11 finds decreasing support as the air expands and tends to pass downward below the level of the deflectors such tendency being preferably accentuated by the provision of the inclined top plate 12, or other means for positively causing the material in space 11 to travel downward. Such material as passes the end of the deflector 9, however, enters the incoming air with reduced force, at a point where the expansion of the incoming air has so reduced its density that the dust particles may probably pass readily therethrough to the casing wall.

It is preferable that there be always left a space between the deflector 10 and the air outlet, that any dust entering the vortical whirl may be centrifugally maintained out of the path of air escape until the end of

the deflector 10 is reached and the dust projected without the vortical whirl area into the incoming air. The cutting away of the deflector 10, at 10^a, I believe also assists in preventing dust escape from the air-outlet, as the expansion of the air in space 11 creates a vacuum-tendency which establishes an induced draft through opening 10^a, so that dust following the deck of the casing readily passes therethrough.

In the lower portion of the machine, the vortical action is substantially concentric, some distortion being caused by the eccentricity of the dominant whirl above, but not enough to materially affect the working of the machine.

While I have herein described with some particularity one embodiment of my invention, it will be apparent that numerous modifications might be made therein without departure from the spirit and scope of my invention.

Having thus described my invention, what I claim and desire to secure by Letters Patent of the United States, is:

1. In a centrifugal dust collector, a structure inclosing an area wherein the air tends to whirl, provided with a tangential inlet, an air outlet and a dust outlet, and a plurality of deflectors, including between their lateral faces an elongated expansion space gradually increasing in width in the direction of air movement.

2. In a centrifugal dust collector, a structure inclosing an area wherein the air tends to whirl provided with a tangential inlet, an air outlet and a dust outlet, and a plurality of vertical deflectors, curved in plan, including between their lateral faces an elongated expansion space arcuate in plan, gradually increasing in width in the direction of air movement and located in eccentric relation to the casing axis.

3. In a centrifugal dust collector, a structure including an area wherein the air tends to vortically whirl, provided at its upper end with a tangential inlet, in its top with an air outlet, and in its base with a dust outlet, and a plurality of deflectors, arranged in overlying relation throughout a major portion of their extent at different radial distances from the center of the area, said deflectors in plan being both curved throughout their overlapping portions and eccentric to the center of said area, and gradually approaching said center in the direction of air movement, the radially outermost deflector extending from an initial point of contact with the including structure, and from substantially the top of said area to the bottom of the inlet.

4. In a centrifugal dust collector, a casing structure wherein dust-laden air may move centrifugally to mass the dust, and two eccentric curved deflectors therein, one

extending from the casing wall gradually toward the casing axis, and terminating between said wall and axis, and the other extending from a point separated from the casing wall gradually toward a point nearer the casing axis than the end of the first said deflector, said casing providing an air outlet opening to the eccentric whirl area partially defined by the deflectors, a dust outlet, and a tangential air inlet to the area radially outside of the first said deflector, whereby the inner deflector diverts relatively dustless air into an eccentric vortical whirl to which the air outlet opens, and the outer deflector diverts substantially the entire dust-laden air portion for delivery outside of the eccentric vortical whirl to the incoming dust-laden air.

5. In a centrifugal dust collector, a casing structure wherein dust-laden air may move to centrifugally mass the dust, a tangential inlet thereto, a dust outlet therefrom, a deflector extending from a point out of contact with the casing wall eccentrically inward toward the axis of the casing to a point between the air outlet and the casing wall, means between said deflector and the casing wall for downwardly directing dust passing between the casing wall and the radially outer end of said deflector, said casing providing an air outlet opening to the whirl area within, and partially defined by, said deflector.

6. In a centrifugal dust collector, a structure wherein moving dust laden air tends to centrifugally mass its dust, a tangential inlet thereto, a dust outlet therefrom, and a plurality of deflectors arranged in overlying relation to form therebetween an expansion space, the deflectors being disposed to establish an eccentric vortical whirl in the upper portion of the structure, and an air outlet opening into the area of said eccentric vortical whirl.

7. In a centrifugal dust collector, a structure including an area, vertically substantially uninterrupted and tapering to a dust outlet at the bottom, a tangential inlet in the upper part thereof wherethrough dust laden air may be introduced to move within the structure to centrifugally mass its dust, a plurality of deflectors, one arranged to deflect substantially dustless air from within the massed dust in the upper plane of the casing into a vortical whirl eccentric to the casing, and the other arranged to deliver the massed dust with reduced force to the air body without said eccentric vortical whirl, and an air outlet opening into said eccentric vortical whirl.

8. In a centrifugal dust collector, a structure wherein dust laden air in motion tends to centrifugally mass its dust, a tangential inlet thereto, a dust outlet therefrom, an air outlet in the top thereof, and a plurality of

deflectors arranged in overlying separated relation to form therebetween an expansion space, one of said deflectors being adjustable, and said deflectors being disposed to

5 establish an eccentric vertical whirl in the upper portion of the structure in the area into which the air outlet opens.

In testimony whereof I hereunto set my hand in the presence of two witnesses.

ORVILLE M. MORSE.

In the presence of—

WILLIAM B. KNICKERBOCKER,
JOHN L. BENTLEY.
